UNITED STATES PATENT OFFICE.

CHARLES SCHAFER, OF NEW YORK, N. Y.

DESIGN FOR CAPITAL LETTERS.

SPECIFICATION forming part of Design No. 15,011, dated May 20, 1884.

Application filed March 26, 1884. Term of patent 7 years.

To all whom it may concern:

Be it known that I, CHARLES SCHAFER, of the city, county, and State of New York, have invented a new and original Design for Capital Letters, of which the following is a full, clear, and exact description, reference being had to the accompanying drawing, making part of this specification.

This design relates to a new and original alphabet of capital letters. The lines of the letters are represented as consisting of leaves and flowers, as shown, which are combined in such a manner that the letters have the same general characteristics, the letters being, furthermore, so designed that they occupy more or less the same space.

Alphabet letters have been used heretofore

in which curved stems having elongated tapering leaves are combined with flowers having curved stems, and I therefore do not claim 20 the combination of stems, leaves, and flowers, broadly.

Having thus described my invention, I claim as new and desire to secure by Letters Patent—

The design for capital letters, as herein 25 shown and described.

In testimony that I claim the foregoing as my invention I have signed it this 17th day of March, 1884.

CHAS. SCHAFER.
